Primary Examiner — George D. Kirschbaum*Assistant Examiner* — Marie J Edwards(74) Attorney, Agent, or Firm — Jason H. Foster;
Kremblas & Foster(57) CLAIM

The ornamental design for a video game playing glove, as shown and described.

DESCRIPTION

FIG. 1 is a perspective view of a video game playing glove showing my new design;

FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.
